UNITED STATES PATENT OFFICE.

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 12,560, dated November 1, 1881.

Application filed September 24, 1881. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of a light-faced condensed letter, the terminations of which are curved, terminating in a dot flattened out.

In the A, H, and M the looped ornamenta-

tion is employed for the central portion of the letters.

In the figures the character of the designs is preserved.

What I claim, and desire to secure by Letters Patent, is—

The design for a font of printing-type, as shown and described.

WM. W. JACKSON.

In presence of—

Wm. B. MACKELLAR,
HERMAN METIUS.
